UNITED STATES PATENT OFFICE.

HENRY HEATH, OF NEW YORK, N. Y., ASSIGNOR TO FISK, CLARK & FLAGG, OF SAME PLACE.

RETAINER FOR NECKTIES.

SPECIFICATION forming part of Letters Patent No. 292,308, dated January 22, 1884.

Application filed November 12, 1883. (No model.)

To all whom it may concern:

Be it known that I, HENRY HEATH, of the city, county, and State of New York, have invented a new and useful Improvement in Retainers for Neckties; and I do hereby declare that the following is a full and exact description thereof, reference being had to the accompanying drawings, and to the letters of reference marked thereon, making a part of this specification.

My invention relates to an improvement in retainers for neckties.

It consists in a retaining device for neckties, constructed of a stiffening-piece of card-board or its equivalent, fitted with a wire which, being doubled upon itself in the middle, is secured to one side of the stiffening-piece by an eyelet engaging its loop, while its ends, extending to the edge of the piece, are so bent and folded over said edge as to be steadied thereby and project therefrom over the opposite face of the piece in position, when the stiffening-piece is properly secured in the bow and the bow is made fast upon the neck, to serve to engage the collar-button, and thus prevent the bow from working upward out of place.

In the accompanying drawings, Figure 1 is a view of the rear or under side of a necktie-bow embodying my invention; Fig. 2, a transverse section in line $\alpha\alpha$ of Fig. 1; Fig. 3, a view of the front, and Fig. 4 a view of the rear, face of the stiffening-piece detached, illustrating the attachment of the wire retainer thereto; Fig. 5, an end view of same, and Fig. 6 a perspective view of the wire detached.

A, Figs. 2 and 5, represents a bit of card-board or other material suitable as a foundation or stiffening for the bow of a necktie.

B represents a piece of wire bent upon itself in the middle in the form of an eye, e , Fig. 6, and whose ends, extending from the eye parallel with each other for a suitable distance—about equal to one-half the width of the stiffening-piece A, to which the wire is to be attached—are doubled upon themselves, as at d , and spread slightly apart to form the two diverging arms or prongs $e e$, adapted to en-

gage between them a collar-button. The wire retaining device B thus formed is attached to the stiffening-piece A by inserting the latter into the bend of the wire, so that its middle eye, e , shall be upon the rear, and its prongs $e e$ upon the front, side of the stiffening-piece, and it is secured thereto by means of an eyelet or tubular rivet, E, inserted through the eye e , and through an aperture in the piece A and upset therein, so as to firmly clamp the wire B upon said piece. The portion of the wire including the eye e is preferably flattened, to make a neater fit thereof against the piece A. The engagement of the bend d of the wire with the edge of the piece A serves to prevent the wire from working loose or becoming displaced, and thus completes the secure attachment of the two together. The stiffening-piece A, with its attached retainer B, is slipped into the open end of the double piece constituting the band of the bow F, leaving the ends $e e$ projecting out therefrom upward from near the lower edge of the bow, as illustrated in Figs. 1 and 2, in position to embrace between them the collar-button when the necktie is secured about the neck. The arms $e e$ of the retainer will thus serve to prevent the bow from slipping up upon the collar or from moving laterally. Its construction is simple, it is cheaply made, and it is readily attached to the stiffening-piece, which in turn may be readily united to the bow, as set forth, forming a neat efficient retaining device.

I am aware that bows for neck-wear have heretofore been provided with wire hooks and loops in different forms, to serve as retaining devices therefor.

My invention differs from all others in that the retainer is constructed of a stiffening-piece to fit in the bow of the tie, combined with a wire so bent as that being secured to the stiffening-piece on one side thereof it shall bend over the edge of said piece and project therefrom on the opposite side in form to embrace the collar-button between two upwardly-projecting arms.

I claim as my invention—

A necktie-retainer constructed substantially

as herein described, and consisting of a stiffening-piece, as A, a bit of wire, as B, doubled upon itself in the middle and formed into an eye, a device, as E, led through the eye to secure the wire upon one side of the stiffening-piece, and projecting ends, as e e, extending from the eye to the edge of the stiffening-piece on the one side thereof, and bent over said edge to constitute diverging arms upon

the opposite side, adapted to embrace a collar-¹⁰ button, substantially as set forth.

In testimony whereof I have signed my name to this specification in the presence of two subscribing witnesses.

HENRY HEATH.
